(57) **CLAIM**

The ornamental design for a container with floral lid, as shown and described.

DESCRIPTION

FIG. 1 is a top front perspective view of a container with floral lid showing my new design, shown in an open position;

FIG. 2 is a top right side perspective view thereof;

FIG. 3 is a front elevation view thereof;

FIG. 4 is a rear elevation view thereof;

FIG. 5 is a right side elevation view thereof, with the left side elevation view being a mirror image thereof;

FIG. 6 is a top plan view thereof;

FIG. 7 is a bottom plan view thereof; and,

FIG. 8 is a top front perspective view of the container with floral lid, shown in a closed position.

(Continued)

The broken lines shown in the drawings depict portions of the article that form no part of the claimed design.

1 Claim, 4 Drawing Sheets
